UNITED STATES PATENT OFFICE.

HENRY O. NIELSEN, OF TREMONTON, UTAH.

PERMUTATION LOCK.

1,408,772.

Specification of Letters Patent.

Patented Mar. 7, 1922.

Application filed April 18, 1921. Serial No. 462,219.

To all whom it may concern:

Be it known that I, HENRY O. NIELSEN, a citizen of the United States, residing at Tremonton, in the county of Boxelder, State of Utah, have invented certain new and useful Improvements in Permutation Locks; and I do hereby declare the following to be a full, clear, and exact description of the invention, such as will enable others skilled in the art to which it appertains to make and use the same.

This invention relates to combination or permutation locks, and more especially to those having rotating tumblers; and the object of the same is to greatly simplify a lock of this character and adapt it for use on the door of a safe or vault so that when the same is closed no part of the lock is exposed excepting the knob or handle and the edges of the tumblers, but when the door is open the parts of the lock may be readily reached for cleaning, repair or replacement.

One practical means for carrying out the invention is set forth below and shown in the drawings wherein:

Figure 1 is a horizontal section through part of a safe door and this lock, showing the bolt as retracted.

Figure 2 is a vertical section through the knob spindle, showing in section certain of the parts connected therewith.

Figure 3 is an inner end elevation of the spindle, showing the bolt partly in section and midway between locked and unlocked positions.

Figure 4 is a detail section on the line 4-4 of Figure 1.

Figure 5 is a perspective detail of one tumbler.

In the drawings the letter D designates the door which is to be locked when closed into coactive position with a wall W, and B is a bolt slidable longitudinally within a suitable guide in the door and adapted when projected or shot to enter a keeper or hole H in the wall W, whereas when it is retracted the door may be swung open. It will be understood without further illustration that, when this invention is applied to the lock on a safe or vault, the bolt herein shown is only one of many mounted within the door and connected so that the movement of the master bolt moves them all, the purpose being to lock the door to the safe wall at a plurality of points; and therefore, instead of connecting this lock with the master bolt

as herein shown, it might be connected with the bar extending between a plurality of bolts, and the present invention is to be understood as sufficiently broad in scope to cover this idea. Also, while a safe door usually swings open and closed, it is quite possible that this invention could be applied to a lock which prevented a sliding movement of the door or partly intended to be locked by it.

Coming now to the details of the present invention, the spindle 1 has a handle or knob 2 at its outer end and preferably has its inner portion reduced at 3 so as to leave a shoulder 4 and again reduced at 5 so as to leave a second shoulder 6 spaced from the first shoulder for a purpose yet to appear. Mounted upon the reduced portion 5 is a sleeve 7 held thereon by any suitable means at the inner end of the spindle. As herein shown, a lever 8 projects radially from a nut 9 which is screwed onto the threaded inner end 10 of the spindle against the inner end of the sleeve 7, and the parts held very tightly in place by a jam nut 11. Yet I wish it understood that this description of parts merely defines one construction which may be given them so that they can be assembled, the handle end of the spindle being inserted from the front of the door D and the remaining parts applied from the inner side of the door, and in their assembly the parts yet to be described can be also applied. Rotatably mounted on the reduced portion 3 of the spindle is a collar 13 from which rigidly projects a dog 12. Surrounding the sleeve 7 is a coiled expansive spring 17 whereof one end contacts with the bearing 15 in which the spindle is journaled and the other end contacts with the nut 9 so that the tendency of the spring is to draw the spindle inward as far as permitted by the collar 13. The knob may be formed in the shape of a handle which is herein shown as projecting to the left from the spindle, and at such time the dog 12 will project to the right and the lever 8 will stand nearly upright, or a little to the right of the position shown in Figure 3 where it is midway the length of its stroke effected by turning of the spindle. The numeral 18 designates a spring or spring actuated detent carried by the door or the casing of the lock and so disposed that its tip would stand in the path of the lever 8 if the latter were swung to the left in Figure 3, which would shoot

the bolt as yet to be described; and therefore, in order to swing the lever in the opposite direction and retract the bolt, it is necessary first to move the lever out of line with the tip of this detent, which movement is effected by drawing the entire spindle forward in its bearing, the spring 17 yielding to permit. Any suitable means may be employed for connecting the lever with the bolt or the series of bolts, but such connection is typically illustrated herein by showing the lever as passing upward through an opening 19 in the bolt.

The description thus far given includes 15 mean for retracting or projecting the bolt by the oscillations of a knob spindle intended to be actuated manually, and means for latching or locking the spindle against movement after it has been turned to project the bolt. This means, as stated, consists of a detent standing in the path of a lever projecting radially from the spindle but yielding to permit the lever to move to position to shoot the bolt. Therefore, in 20 order to retract the bolt, it is necessary first to slide the spindle in a direction which will move its lever out of line with said detent. This sliding is accomplished manually by the operator who grasps the knob and draws 25 it forward, and an important feature of this invention consists in the provision of an extremely simple permutation mechanism including manually operated tumblers for preventing such forward movement until the 30 tumblers are set to the proper combination.

The numeral 20 designates a stud here shown as standing horizontal, fixed at its outer end within some portion of the lock casing, and projecting directly toward the 35 spindle 1, and the front side of this stud has a deep groove or channel 22. The numerals 23 designate tumblers, each being a ring mounted for rotation around the stud as seen, and each having a deep or master groove 24 and a large number of shallow or blind grooves 25. These tumblers are confined in any suitable manner on the stud and will lie side by side and in contact with each other as seen in Figure 1, their forward 40 edges being exposed through a suitable opening 26 in the lock casing at the surface of the door, and such edges having 45 graduations and letters or numbers 27 thereon, opposite their internal grooves. 50 For sake of example let us assume that the master grooves of the first, second, third and fourth tumblers herein shown are respectively opposite their numbers 1, 2, 3, and 4. The dog 12 projects from its collar 55 13 into the channel 22 in the stud 20, and when the spindle stands at the inner limit of its sliding movement this dog is at the inner end of the channel and its active front edge disengaged from all the grooves in 60 the tumblers.

Now when it is desired to unlock the door D, the operator spins the tumblers on the stud until he produces the proper combination of letters or numbers, which in the present instance would occur when the units 70 on the tumblers made up the number 1234, and at this time the several master grooves 24 would stand directly opposite the active front edge of the dog 12. Now he grasps the handle or knob 2 and draws forward on the 75 spindle, which movement is permitted because the dog in its forward movement may pass into the aligned master grooves. Such forward movement moves the lever 8 out of line with the detent 18, and then the operator 80 may turn the spindle and the swinging of the lever retracts the bolt B and the door can be drawn open. Later when the door is closed, turning of the spindle in the opposite direction moves the lever alongside 85 the detent which yields to permit such movement, and when the lever has passed the tip of the detent and the bolt has been shot, the detent springs behind the lever and prevents its rearward movement to retract the 90 bolt.

Attention is invited to the utility of the blind grooves 25 which, of course, are shallower than the master grooves in any tumbler and which by preference will be disposed 95 opposite the respective graduations or numbers 27. Without these grooves a skillful cracksmen might manipulate the combination and by the "feel" and "sound" of its tumblers ascertain when their grooves come 100 successively opposite the dog 12, and finally open the lock. But with the blind grooves the structure has the same feel and sound for each tumbler as it would if he had properly set it, and he is mystified and baffled in his efforts. The drawings show four tumblers side by side, but the invention is not to be limited in this respect. The combination can be changed by substituting other tumblers at any time, or even by transposing the position of those first employed. The parts are accessible from the inside of the door when open, and nothing need project beyond its face excepting the handle or knob which itself need only be large enough 115 to be grasped by the fingers. While I have described the bolt B as being that which locks the door, it is of course possible on large safes or vaults that this bolt shall be that which locks the main bolt or bolts 120 against retraction, and they in turn could be larger and heavier and retracted by a separate mechanism after the bolt B herein had first been retracted. In these and other respects I reserve the widest latitude com- 125 mensurate with the claims below.

What is claimed as new is:

1. In a lock, the combination with a spindle mounted to oscillate and to slide, mechanism tending to hold it at one ex- 130

treme of its axial movement, and a bolt actuated by its oscillation; of a spring detent, an arm on the spindle normally engaging said detent, said spindle being slidable 5 out of its said extreme position, to disengage the arm from the detent.

2. In a lock, the combination with a spindle mounted to oscillate and to slide, permutation mechanism adapted to be set 10 to hold it at one extreme of its axial movement, and a bolt actuated by its oscillation; of a detent, and a lever on the spindle swung in a path intersecting said detent as the spindle is oscillated and latched automatically 15 by such detent when the bolt is projected, the lever being moved out of such path when the spindle is slid out of its said extreme position.

3. In a lock, the combination with a 20 spindle mounted to oscillate and to slide in its casing, a spring bearing it normally to the rear therein, permutation mechanism for preventing or permitting its forward movement, and a bolt actuated by the oscillation 25 of the spindle; of a detent member on the casing, and a lever member fast on the spindle and moved thereby, said members engaging each other when the spindle is oscillated while in its normal position but 30 clearing each other when the spindle is moved forward.

4. In a lock, the combination with a spindle mounted to oscillate and to slide in its casing and having a knob on its front 35 end, a spring bearing it normally to the rear within such casing, tumblers adapted to be set to prevent or to permit its forward movement, a bolt, and connections between the bolt and the spindle whereby the oscillation 40 of the latter moves the bolt; of a detent carried by the casing, an arm carried by and movable with the spindle, the end of the arm swinging in the plane of the end of the detent when the spindle is oscillated while 45 in its normal position but moved wholly out of said plane when the spindle is drawn forward, the end of said detent being yielding, for the purpose set forth.

5. In a lock, the combination with a 50 spindle mounted to oscillate and to slide in its casing and having a knob on its front end, a spring bearing it normally to the rear within such casing, tumblers adapted to be set to prevent or to permit its forward

movement, and a bolt having a transverse 55 opening; of a lever fast on the spindle and projecting through said opening for moving the bolt as the spindle is oscillated, and a spring detent fast on the casing and having its tip standing in the path of said lever 60 as the latter swings while the spindle stands in its normal position, movement of the spindle forward carrying the lever out of position to be engaged by the detent.

6. In a permutation lock, the combination 65 with a spindle mounted to oscillate and to slide, a bolt actuated by its oscillation, and means for latching the bolt when projected; of a collar swiveled on the spindle, a dog projecting therefrom, a stud having a channel 70 receiving said dog, and a plurality of tumblers rotatably mounted around the stud and each having an internal groove adapted to be alined with said channel.

7. In a permutation lock, the combination 75 with a spindle mounted to oscillate and to slide, a bolt actuated by its oscillation, and means for latching the bolt, when projected; of a dog swivelly carried by and projecting radially from said spindle, a plurality of 80 annular tumblers encircling the dog and each having a master groove and a plurality of blind grooves in its inner periphery, and a bearing on which the tumblers are rotatably mounted, the bearing having a channel 85 in which the dog is movably disposed.

8. In a permutation lock, the combination with a knob spindle mounted to oscillate and to slide within its casing and having spaced shoulders on its body, a lever 90 detachably mounted on its inner end, a spring on the spindle between the lever and a fixed part of the casing, a bolt reciprocated by the swinging movements of said lever, and means for latching said bolt when projected 95 and for releasing it when the spindle is drawn forward; of a collar swiveled on the spindle between its shoulder, a dog projecting therefrom, and a plurality of annular tumblers movably mounted around the dog 100 and each having in internal groove, as described.

In testimony whereof, I affix my signature, in the presence of two witnesses.

HENRY O. NIELSEN.
